UNITED STATES PATENT OFFICE.

OLIVER R. MEREDITH, JAMES I. GALLACHER, AND CHARLES F. JONES, OF SALT LAKE CITY, UTAH TERRITORY.

TRUNK.

SPECIFICATION forming part of Letters Patent No. 310,704, dated January 13, 1885.

Application filed November 4, 1884. (No model.)

To all whom it may concern:

Be it known that we, OLIVER R. MEREDITH, JAMES I. GALLACHER, and CHARLES F. JONES, all of Salt Lake City, in the county of Salt Lake and Territory of Utah, have invented a new and Improved Trunk-Corner, of which the following is a full, clear, and exact description.

The object of our invention is to provide a new and improved corner-piece for the front corners of trunks, which corner-piece also serves as a latch-frame.

The invention consists in a trunk corner-piece provided with a hasp, and a trunk corner-piece provided with a hook-lug, over which the hasp can be passed. The first-mentioned corner-piece is secured on the corner of the trunk-body and the other on the cover.

Reference is to be had to the accompanying drawings, forming part of this specification, in which similar letters of reference indicate corresponding parts in all the figures.

Figure 1 is a perspective view of our improved trunk-corner. Fig. 2 is a sectional plan view of the same. Fig. 3 is a cross-sectional view on the line *x x*, Fig. 1. Fig. 4 is a cross-sectional view of the same on the line *y y*, Fig. 1.

The angle pieces A B, made of cast metal or otherwise, are secured on the cover A' and the trunk-body B', respectively, the bottom edge of the piece A being flush with the bottom of the cover, and the top edge of the piece B is flush with the top edge of the trunk-body. The height of each piece is greatest at the corner, and decreases toward the ends of the arms, the outer edges being stepped from the corner toward the ends.

From the bottom edge of the top piece, A, two lugs, C, project down on each side, the inner edges of the lugs being flush with the inner surface of the angle-piece, and the outer surfaces of the said lugs and their bottom edges being rounded. The front sides of the lugs C set back a short distance from the outer surface of the angle-piece. Pockets D are formed in the upper edge and rear surface of the bottom angle-piece, B.

From the bottom edge of the top angle-piece, A, a hook-lug, E, projects downward

at the front of the trunk, and is provided on its free end with an outwardly-projecting prong, F. A recess, G, is formed in the front of the bottom angle-piece, B, for securing the lug E. A hasp, H, is hinged on the front of the piece B, and is adapted to be swung against the front of the said angle-piece, and it is provided at its free end with a slot, J, into which the prong F projects when the hasp is folded against the angle-piece, thus holding the cover on the trunk. The inner end of the swinging or hinged hasp H is held in a casing, L, on the front of the angle-piece, the said casing containing a spring, M, acting on the inner end of the hasp, and serving to hold it in place. When the cover is swung down, the lugs C pass into the pockets D, and the lug E passes into the recess G. The hasp H is then swung against the face of the angle-piece B, the prong F passing into the slot J in the hasp, and thus locking the cover on the trunk. The angle-pieces strengthen and protect the corners, and thus make the trunk more durable.

Having thus described our invention, what we claim as new, and desire to secure by Letters Patent, is—

1. The combination, with the trunk corner-piece A, having a hook-lug, E, of the corner-piece B and the hasp H, hinged on the same, substantially as herein shown and described.

2. The combination, with the trunk corner-piece A, having lug C and a hook-lug, E, of the corner-piece B, having recesses D and G, and of the hinged hasp H, substantially as herein shown and described.

3. The trunk corner-piece A, having upon the lower edge the hook-lug E, in combination with the apertured latch H, having a pintle at its bifurcated end, and the case L, having a spring, M, bearing upon said pintle, substantially as and for the purpose set forth.

OLIVER R. MEREDITH.
JAMES I. GALLACHER.
CHARLES F. JONES.
